Patented Nov. 19, 1918.

FIG. 1 -

UNITED STATES PATENT OFFICE.

WILLIAM T. WHEELER, OF NASHVILLE, OREGON.

COMBINATION-TOOL.

1,285,513.

Specification of Letters Patent. Patented Nov. 19, 1918.

Application filed February 21, 1917. Serial No. 150,090.

To all whom it may concern:

Be it known that I, WILLIAM T. WHEELER, a citizen of the United States, residing at Nashville, in the county of Lincoln and 5 State of Oregon, have invented certain new and useful Improvements in Combination-Tools, of which the following is a specification.

This invention relates to a combination 10 tool and more particularly to a tool including a square and a hand saw adapted to be used by artisans so that the back edges of the saw blade and the handle therefor may be manipulated for measuring and determining 15 angles without the use of the ordinary square and protractor commonly employed for this purpose.

One of the objects of the invention is to provide an ordinary hand saw with a handle 20 that will be rotatable instead of fixedly mounted to the saw blade and provided with means for fixing the movable handle at any desired angle with respect to the back edge of the saw blade.

Another object of the invention is the provision of a graduated disk associated with 25 the pivot of the saw handle and adapted to coöperate with one edge of the handle for indicating the angular disposition of the 30 handle when the same is moved on its pivot thereby providing a protractor for use in determining various angles.

A further object of this invention is the provision of a combination tool which consists of comparatively few parts and is simple in construction, but durable and well 35 adapted to withstand the rough usage to which devices of this character are ordinarily subjected.

For a full description of the invention and the advantages and merits thereof, reference is to be had to the following description and the accompanying drawings, wherein is illustrated the preferred form of my 45 invention, in which:

Figure 1 is a side elevation, part of the handle being broken away.

Fig. 2 is a longitudinal section on the line 2—2 of Fig. 1.

Fig. 3 is a view similar to Fig. 1 showing the handle disposed in the position it as-

sumes when the device is being used as a square, and

Fig. 4 is a detail perspective view of the pivot pin. 55

Referring to the drawing, wherein is illustrated the preferred form of my invention, and in which like numerals of reference indicate corresponding parts throughout the several views, the saw blade 1 is of the type 60 commonly employed in connection with hand saws. The end of the saw blade to which the handle is attached is curved to form a substantially semi-circular end edge and which is provided with a plurality of 65 teeth 3'. An aperture is provided in the saw blade at the center of the semi-circular end portion. The handle 2 is of the ordinary construction and is provided with a slot 3 in which the semi-circular end of the saw 70 blade is arranged.

One end edge of the handle is provided with projections 4, the terminals of which are cut at right angles with respect to the longitudinal edge of the handle to provide 75 the straight ends 4'. These straight ends 4', being in the same plane with each other, form one side of a right angle, the other side of which is formed by the edge 5 of the saw blade 1. These extensions also form a 80 protection for the protractor hereinafter described.

Integrally formed with the handle 2 and extending from the edge thereof is a semi-circular disk portion 6 which is bifurcated 85 as is the inner portion of the handle by the slot 3. The disk 6, therefore, is divided into two halves which embrace the saw as clearly shown by Fig. 2 of the drawing. Each side of the disk has a beveled edge 7 provided 90 with a plurality of circumferentially spaced graduations forming a part of the protractor. An opening 8 is formed in the handle and the center of this opening is in registry with the straight forward edge 2' of the 95 handle. Half of the opening is thereby formed in the handle and the other half is formed in the semi-circular disk portion 6. A pivot pin 9 is extended through the opening 8 and also through an opening formed 100 in the saw blade 1 and each end of the pivot pin is cut away for forming oppositely dis-

posed semi-cylindrical portions each of which has an opening 10 for receiving a suitable fastening screw for fastening the pivot pin to the handle so that the pivot pin moves 5 with the handle when the latter is turned and the pin thereby rotates in the opening in the saw blade.

An opening 11 is provided in the handle and communicates with the slot 13. The 10 knocking pin 12 is extended through the opening 11 and has a head 13' for forming the locking pin to be withdrawn when unlocking the same. The opposite end of the locking pin engages the teeth 3' and is normally held in engagement therewith by a 15 coil spring 14.

As shown by Fig. 1 of the drawing the device is in the position which it will assume when being used as a common hand saw. 20 The locking pin 12 engages the teeth 3' and locks the handle against movement with respect to the saw blade. It is to be noted that the back edge of the handle is perfectly straight and forms a straight edge 15 25 which is a continuation of the straight edge 5 when the device is in this position. Now, to change the device so the same may be used as a square, it is merely necessary to release the locking pin 12 and rotate the 30 handle until the straight edge 15 is disposed at right angles to the straight edge 5. It is to be noted that one wall 15' of the slot 3 is perfectly straight and at right angles to the straight edge 15. When this straight 35 wall of the slot contacts with the edge 5, the straight edge 15 will be at a perfect right angle to the straight edge 5, and the locking pin may then be permitted to engage one of the teeth for holding the device 40 in this position as clearly shown by Fig. 3 of the drawing. A short straight line 16 is provided on the saw blade in registry with the center of the disk 6 and the graduations of the disk will register with this line so 45 that the handle may be turned to any desired angle indicated by the marked graduations on the beveled edge of the disk. This will indicate the angle at which the straight edge 15 is disposed with respect to the 50 straight edge 5 and in this manner any angle may be measured in the same manner as is the case with the ordinary protractor.

When the device is being used as an ordinary hand saw, the projections 4 will protect 55 the protractor disk 6 since it is obvious that when the saw is moving through a piece of work the projection will contact with the work if the saw is thrust too far forwardly thereby preventing contact with the disk 6. 60 Furthermore, a straight line may be drawn by means of the edge 5 which will be at right angles to the edge of any piece of work with which the projections 4 are

brought into contact. This construction thereby affords a substitute for the ordinary 65 try-square.

From the foregoing it will be observed that a very simple and durable combination tool has been provided the details of which embody the preferred form. I desire it to 70 be understood however, that slight changes in the minor details of construction may be made without departing from the spirit of the invention or the scope of the claims hereunto appended.

75 I claim:

1. A tool comprising a blade having a handle pivotally mounted on one end thereof, a semi-circular disk portion carried by the said handle, the said disk portion and 80 the handle being bifurcated by a slot, the said blade being received in the slot whereby portions of the said disk are disposed on opposite sides of the blade, each side of the disk having a beveled edge provided with 85 graduations, there being a short straight line provided on the blade to register with any of the graduations on the said disk for indicating the angular portion of the handle when swung on its pivot. 90

2. A tool comprising a blade having a handle pivotally mounted on one end thereof, a semi-circular disk portion carried by the said handle, the said disk portion and the handle being bifurcated by a slot, the 95 said blade being received in the slot whereby portions of the said disk are disposed on opposite sides of the blade, each side of the disk having a beveled edge provided with graduations, there being a short straight line 100 provided on the blade to register with any of the graduations on the said disk for indicating the angular position of the handle when swung on its pivot, a pivot pin extending through the blade and handle, each end 105 of the pivot pin being formed with oppositely disposed semi-cylindrical portions each having an opening, and a fastening screw extended through the opening in the pin and attached to the handle whereby the said pin 110 will rotate with the handle.

3. A combination tool comprising a handle, a blade carried by the handle and pivotally connected thereto, means for locking the handle in any desired angular position 115 with respect to the blade, a protractor attached to the handle for indicating the angular position thereof with respect to the blade, and means carried by the handle for protecting the protractor when the blade is 120 in use.

4. A combination tool comprising a handle, a blade carried by the handle and pivotally connected thereto, means for locking the handle in any desired angular position 125 with respect to the blade, a protractor at-

tached to the handle for indicating the angular position thereof with respect to the blade, means carried by the handle for protecting the protractor when the blade is in use, the 5 said means having straight portions disposed at right angles to the back of the blade for forming a try-square.

In testimony whereof I affix my signature in presence of two witnesses.

WILLIAM T. WHEELER.
